US00D816080S

(12) **United States Design Patent** (10) **Patent No.:** **US D816,080 S**
(45) **Date of Patent:** **** Apr. 24, 2018**

(54) **SMART BRACELET**

(71) Applicant: **HUAWEI TECHNOLOGIES CO., LTD.**, Shenzhen (CN)

(72) Inventors: **Biliu Chen**, Shenzhen (CN); **Zhaozhao Liu**, Shenzhen (CN)

(73) Assignee: **Huawei Technologies Co., LTD. (CN)**

(**) Term: **15 Years**

(21) Appl. No.: **29/590,867**

(22) Filed: **Jan. 13, 2017**

(30) **Foreign Application Priority Data**

Jul. 14, 2016 (CN) 2016 3 0321780

(51) **LOC (11) Cl.** **14-02**

(52) **U.S. Cl.**

USPC **D14/344**
